BOX FOR DISPENSING HOT FOOD PRODUCTS OR THE LIKE

Edward W. Schroeder, Silver Spring, Md., assignor to Marriott-Hot Shoppes, Inc., a corporation of Delaware

Filed Apr. 3, 1964, Ser. No. 79,326

Term of patent 14 years

(Cl. D58—12.6)

FIG. 1

FIG. 2

FIG. 3

FIG. 5

FIG. 1 is a perspective view of the side and one end of a box for dispensing hot food products or the like, showing my new design;

FIG. 2 is an elevational view of the side opposite that shown in FIG. 1;

FIG. 3 is a top plan view thereof;

FIG. 4 is an end elevational view thereof, and

FIG. 5 is a bottom plan view thereof.

A characteristic feature of my design resides in the combination of a fully closed box top having gabled ends and outwardly bulged end walls below the gables all as shown.

I claim:

The ornamental design for a box for dispensing hot food products or the like, as shown and described.
